UNITED STATES PATENT OFFICE.

HARRY E. FENNO, OF PROVIDENCE, RHODE ISLAND, ASSIGNOR TO GEORGE F. BERKANDER, OF PROVIDENCE, RHODE ISLAND.

DESIGN FOR A PAIR OF GOGGLES.

47,916.

Specification for Design.

Patented Oct. 5, 1915.

Application filed June 7, 1915. Serial No. 32,757. Term of patent 3½ years.

To all whom it may concern:

Be it known that I, HARRY E. FENNO, a citizen of the United States, residing at the city and county of Providence, State of Rhode Island, have invented a new, original, and ornamental Design for a Pair of Goggles, of which the following is a specification, reference being had to the accompanying drawing, forming part thereof.

The figure is a perspective view illustrating my new design of a pair of goggles.

I claim:

The ornamental design for a pair of goggles, as shown.

HARRY E. FENNO.
